UNITED STATES PATENT OFFICE.

CHARLES DAVY, OF SHEFFIELD, ENGLAND.

TRAVELING CRANE.

SPECIFICATION forming part of Letters Patent No. 439,483, dated October 28, 1890.

Application filed May 3, 1890. Serial No. 350,463. (No model.) Patented in England October 25, 1887, No. 14,535, and in France April 3, 1889, No. 197,195.

To all whom it may concern:

Be it known that I, CHARLES DAVY, engineer, of 30 Whitworth Road, Ranmoor, Sheffield, in the county of York, England, have invented new and useful Improvements in Overhead Traveling Cranes, (for which I have obtained Letters Patent in the following countries, namely: England, dated October 25, 1887, No. 14,535, and France, dated April 3, 1889, No. 197,195,) of which the following is a full, clear, and exact description.

In overhead traveling cranes the longitudinal and transverse driving-shafts are usually supported at intermediate points by what are termed "tumbler-bearings"—that is to say, bearings supported by counterweighted, pivoted, or sliding brackets—so that they may be lowered to give passage to the sleeve or mechanism that slides along and takes the power from any point of the shaft. These tumbler-bearings are expensive to construct and maintain and their employment is open to many objections.

The object of my invention is to dispense with the tumbler-bearings and to provide means whereby sliding connection may be maintained with a shaft mounted in ordinary fixed bearings, whether it be the main driving-shaft or the transverse driving-shafts, which transmit power to the hoisting-crab. The means whereby this is effected consist of a toothed drum mounted parallel to the driving-shaft, but on the traveling carriage, to which power is to be transmitted from said shaft, the said drum gearing with spur-wheels keyed on the driving-shaft at distances apart less than the length of the toothed drum, so that the teeth of the latter will always be in gear with at least one spur-wheel on the driving-shaft. The drum is preferably placed above the driving-shaft, so that should the rails get out of parallel with said shaft the drum, although not quite in the same vertical plane with the shaft, will nevertheless still remain in gear with it without causing any undue strains and wear, such as result under corresponding circumstances when tumbler-bearings are used. The traveling carriage referred to may be either the traveling gauntlet or the crab traversing upon said gauntlet, according

as the invention is applied to the longitudinal or the transverse driving-shafts.

Reference is to be had to the accompanying drawings, forming part of this specification, wherein—

55

Figure 1 is a sectional elevation taken on line 1 1 of Fig. 3 of the traveling gauntlet, showing the invention as applied for communicating motion from the main longitudinal driving-shaft to the gearing on the 60 gauntlet. Fig. 2 is an elevation showing the application of the same means of communicating motion from the transverse driving-shaft on the traveling gauntlet to the crab traversed along said gauntlet, and Fig. 3 is a 65 plan view of the entire apparatus.

The same letters of reference serve for like parts in all the figures.

In Fig. 1, A is the main driving-shaft, supported by fixed bearings B, and receiving constant motion in the usual way. It is an ordinary round shaft (instead of being square, as usual) and has a series of spur-wheels C keyed upon it at equal distances apart.

70

D is a toothed drum or spur-wheel of a 75 length greater than the distance between two adjacent wheels C in order that as the drum moves along in the direction of its axis its teeth will slide across those of the wheels C, and will not become disengaged from one of 80 said wheels before being engaged with the next wheel in advance, in order that the drum may be always in gear with the shaft A. In the spaces, or any of them, thus bridged over by the drum the bearings B are situated. In 85 Fig. 1 this toothed drum D is mounted at the end of the traveling gauntlet E, with its axis parallel to and above the main shaft A, and by its means motion is imparted from the main driving-shaft A, through a vertical shaft 90 G, to the reversing cone-shaft H, which is constantly running and gives motion in any suitable manner and at required times to the longitudinal traveling cross traversing and hoisting gears. The reversing and other mechanism used, which form no part of this invention, consist of the usual sets of bevel-wheels I J K, (indicated in Fig. 1 by their pitch-lines only,) the set I, for example, controlling the 95 hoisting-gear on the crab, the set J controlling 100

the gear for propelling the traveling gauntree E along the main rails L, and the set K controlling the gear for propelling the crab F along the rails e (see Fig. 2) of the traveling 5 gauntree E. (See Fig. 1.)

In Fig. 2 the shaft A' is one of the shafts upon the traveling gauntree E, by which motion is imparted to the gear on the crab for hoisting the load, such gear being controlled, 10 as before mentioned, by the mechanism I, (see Fig. 1,) a similar arrangement of shaft, wheels, and drum being used for traversing the crab F on the gauntree. The shaft A' is mounted in fixed bearings B' along the girders E' of the gauntree, and has spur-wheels C' keyed on it, which gear with a toothed drum D', mounted on the crab F, motion being communicated from the drum D' to the hoisting mechanism of the crab by any suitable 15 gearing, which need not be described, as it forms no part of the present invention. In this case the shaft A' receives intermittent motion—that is to say, it is started, stopped, and reversed at required times—by the reversing-clutches or other reversing-gear I, hereinbefore mentioned.

In Fig. 3 the parts A², B², C², and D² are similar to those A', B', C', and D' shown in Fig. 2, but are situated at the opposite side 20 of the gauntree E and crab F. Said gearing A², B², C², and D² is part of the mechanism for traversing the crab F upon the gauntree, and its operation is controlled, as before stated, by the reversing mechanism K. In 25 each case the wheels C, C', or C² are of course so keyed on the respective shafts A, A', or A²

that the teeth of the several wheels on the same shaft shall be in longitudinal alignment with each other, and the teeth of the long wheel or drum D, D', or D² are beveled at the 4c ends, as shown at d, d', and d², to insure their sliding easily into engagement with the teeth of the wheels C, C', or C².

Having now particularly described and ascertained the nature of the said invention 45 and in what manner the same is to be performed, I declare that what I claim is—

In an overhead traveling crane, the herein-described means of transmitting rotary motion from a driving-shaft to gearing on a carriage movable relatively to the said driving-shaft in a direction parallel thereto, consisting in the combination, with the said driving-shaft having spur-wheels keyed upon it at 50 intervals, as described, of a toothed drum 55 mounted on the carriage parallel to said driving-shaft, and of a length greater than the interval between two adjacent-wheels on the driving-shaft so that it will always be in gear with at least one of the wheels on the driving-shaft, as and for the purpose specified.

The foregoing specification of my improvements in overhead traveling cranes signed by me this 24th day of February, 1890.

CHARLES DAVY.
